Primary Examiner — T. Chase Nelson*Assistant Examiner* — Mark Cavanna(74) *Attorney, Agent, or Firm* — Muncy, Geissler, Olds & Lowe, PLLC(57) **CLAIM**

The ornamental design for a medical instrument holder, as shown and described.

DESCRIPTION

FIG. 1 is a left side perspective view of a medical instrument holder according to the present invention.

FIG. 2 is a right side perspective view of the medical instrument holder of FIG. 1.

FIG. 3 is a front perspective view of the medical instrument holder of FIG. 1.

FIG. 4 is a rear perspective view of the medical instrument holder of FIG. 1.

FIG. 5 is a top plan view of the medical instrument holder of FIG. 1.

FIG. 6 is a bottom plan view of the medical instrument holder of FIG. 1; and,

FIG. 7 is a three-quarter perspective view of the medical instrument holder of FIG. 1.

1 Claim, 7 Drawing Sheets(56)
